UNITED STATES PATENT OFFICE.

EMMA HUGHES, OF WICHITA, KANSAS.

DESK OR TABLE ATTACHMENT FOR FURNITURE.

SPECIFICATION forming part of Letters Patent No. 604,008, dated May 10, 1898.

Application filed June 4, 1892. Serial No. 435,488. (No model.)

To all whom it may concern:

Be it known that I, EMMA HUGHES, a citizen of the United States, residing at Wichita, in the county of Sedgwick and State of Kansas, have invented a certain new and useful Improvement in Desk or Table Attachments for Furniture, &c., of which the following is a specification.

My invention relates to desk or bracket attachments for furniture; and the objects of my invention are to produce a superior form of supporting-bracket of this class in which is embodied my improved means for securing various adjustments of the same to different angles and for different purposes, to construct said device in a neat and inexpensive form, and to admit of its ready connection to parts of furniture or other framework, and to produce other improvements which will be more specifically pointed out hereinafter.

These objects I accomplish in the manner illustrated in the accompanying drawings, in which—

Figure 1 is a rear elevation of my device, showing the desk top or plate supported at an angle. Fig. 2 is a side elevation of the same. Fig. 3 is a side elevation showing said device folded in a compact form, and Fig. 4 is a central longitudinal section of the upper portion of the bracket.

Similar letters refer to similar parts throughout the several views.

a represents a clamping-piece having two parallel jaws projecting therefrom, as indicated at *a'*. This clamping-piece has formed therewith on its rear side a flattened disk-shaped projection or arm *b*, through which is formed a central opening. Through a screw-threaded opening of one of the jaws *a'* of the clamp *a* passes a clamping-screw *b'*, having a suitable clamping-head *b*².

c represents a supporting or bracket arm, which has formed on its lower or inner end a disk-shaped body *c'*, which corresponds in form with the projection *b* of the clamp. The central portion of this disk-shaped portion *c'* is held in frictional contact with the clamp *b* by means of a suitable thumb or clamping screw *d*, which, passing through the central opening of the clamp projection *b*, has its threaded end portion engaging with an internal threaded central opening of said por-

tion *c'*. The supporting-arm *c*, which rises from said portion *c'*, enters and is adjustably supported within the lower portion of a suitable tubular body *d'*, the latter being provided with a set-screw *d*⁴, which passes through the side thereof and engages with the surface of the arm *c*. The upper end of this tubular body *d'* is provided, as shown at 55 *d*², with an arm which projects outwardly and upwardly from said tubular body and which has formed therewith a disk-shaped head *d*³, through which is formed centrally, as described for the clamp projection *b* and 60 *b'*, which is shown in Fig. 4 of the drawings, an opening *e*.

f represents a bracket-plate having a flat portion *f'* and a projecting disk-shaped arm *f*². The outer or flattened portion *f'* of this 70 bracket-piece is secured by screws or otherwise to the under side of a desk board or top plate *g*, while the arm *f*² thereof is adjustably secured against the head *d*³ by means of a thumb-screw *g'*, which, as shown in Fig. 4 of 75 the drawings, passes through the opening *e* and engages with the internal threads of a screw-hole *g*², formed in the disk-shaped arm *f*². The desk top or plate *g*, which is thus supported, may be of any desired length or 80 form and is provided, as shown at *h*, with a small doorway or opening therein and a hinged door adapted to close said opening. This desk top or plate may also be provided with a ledge or cleat *i* on one or more sides or edges 85 thereof.

From the construction herein shown and described it will be seen that the clamp portion *a* may be readily connected with any projecting part of a piece of furniture or any 90 framework, such as indicated at *i*², by inserting said framework between the head *b*² of the screw *b'* and the upper jaw *a'* of the clamp *a* and turning said screw against said framework. It is evident that by loosening the 95 screw *d*, moving the arm *c* to the desired position, and again tightening said screw said arm *c* and the tubular portion *d'* may be supported at any desired angle with the clamp. It is also evident that by loosening the set-screw *d* the tubular portion *d'* may be adjusted vertically on the arm *c*, while the adjustable connection of the head of said tubular portion *d'* with the bracket-piece *f* affords 100

a means of adjusting the desk-top portion *g* to any desired angle. In this manner it will be seen that my device is capable of a number of different adjustments and that the 5 means employed for effecting said adjustments are simple and easily operated.

In case the desk-top *g* is used as a photographer's retouching-frame the door *h* may be dropped downward, as shown in Fig. 2 of 10 the drawings, and the doorway covered in the usual manner by the negative to be retouched.

In the construction herein shown and described it will be seen that my improved furniture attachment will admit of the desk-top 15 *g* being supported at such varying heights and angles as may adapt the same for use for different purposes, and, as shown in Fig. 3 of the drawings, said device may be secured in an exceedingly compact form for shipping 20 or storing.

Having now fully described my invention,

what I claim, and desire to secure by Letters Patent, is—

A table-adjusting device comprising a clamp adapted to be secured to a fixed support and 25 formed with a vertically-projecting disk, a rod provided with a vertically-projecting disk on its lower end, said disk being adapted to coact with the disk on the clamp to form a hinge, a sleeve adapted to loosely receive the rod, a 30 thumb-screw for binding the rod in the sleeve, a disk formed on the upper end of the sleeve, a plate adapted to be secured to the under side of a table and formed with a depending disk adapted to coact with the disk on the 35 sleeve to form a hinge, and thumb-screws uniting the respective pairs of disks, substantially as and for the purposes stated.

EMMA HUGHES.

In presence of—

LOU. K. McCALLA,
J. H. TUCKER.
